UNITED STATES PATENT OFFICE.

JULIUS H. POPP, OF HAVEN, KANSAS.

VENDING-MACHINE.

1,219,662.

Specification of Letters Patent. Patented Mar. 20, 1917.

Application filed September 14, 1916. Serial No. 120,145.

To all whom it may concern:

Be it known that I, JULIUS H. POPP, a citizen of the United States, residing at Haven, in the county of Reno and State of 5 Kansas, have invented certain new and useful Improvements in Vending-Machines, of which the following is a specification.

This invention relates to a coin controlled machine, of the vending type and the principal object of the invention is to provide a machine which may be connected with a pump for dispensing gasoline or other liquids, the attachment normally locking the plunger of the pump against vertical movement and temporarily permitting vertical movement of the pump plunger when a coin is inserted.

Another object of the invention is to so construct this device that it may be connected with pumps already in use.

Another object of the invention is to so construct this attachment that when moved to an inoperative position, the plunger may be raised for a limited extent and then lowered, it being impossible to move the plunger with short reciprocating movements after inserting a coin.

Another object of the invention is to so construct this device that after the coin has 30 released the locking mechanism, it will drop into a coin receptacle.

Another object of the invention is to provide a device of the character described which will be very efficient in operation but 35 which at the same time will be comparatively simple in structure.

This invention is illustrated in the accompanying drawings, wherein:—

Figure 1 is vertical sectional view through 40 the device,

Fig. 2 is a transverse sectional view through the machine taken along the line 2—2 of Fig. 1,

Fig. 3 is a vertical sectional view through 45 the machine taken at right angles to the view in Fig. 1.

Fig. 4 is a transverse sectional view through the machine taken along the line 4—4 of Fig. 3.

The housing 10 is provided in its bottom with an opening 11 which registers with an opening 12 in the upper wall of the receptacle 13 in which the money drawer 14 is mounted so that coins may drop from the 55 slide 15 into the money drawer. This slide

15 is slidably mounted upon the track 16 and is provided with side notches 17 in which the coin will fit. When the slide is moved inwardly by means of the plunger 18, normally held in an extended position 60 by the spring 19, the coin after operating the latching mechanism to move the same to a releasing position, drops into the coin drawer and when the latching mechanism is carried upwardly, the plunger and coin carrier will return to the original position.

A rack bar 20 extends vertically in the housing 10 and is provided with rack teeth 21 and 22 which extend in opposite directions, the rack teeth 21 preventing raising 70 of the pump locking slide and the teeth 22 preventing lowering of the pump locking slide. This slide 23 is provided with arms 24 which extend upon opposite sides of the rack bar 20 and further carries a hood 25 provided with side arms 26 which extend upon opposite sides of the rack bar above the arms 24. Latches 27 and 28 are pivotally mounted between the arms 24 and are connected by means of the links 29, the links 80 being pivotally connected with the latch 27 and pivotally and slidably connected with the latch 28 as clearly shown in Fig. 1. Springs 30 and 31 are provided to yieldably hold the latches in an operative position, the spring 30 being stronger than the 85 spring 31 so that when the device is in the position shown in Fig. 1, the latch 27 will be in an operative position and the latch 28 in an inoperative position. It should be noted that the latch 27 is provided with a handle 32 extending into the slot 11 so that when the plunger 18 is moved inwardly, the coin placed in the groove 17 of the coin carrier 15, will engage this latch and swing 90

the same to an inoperative position thus permitting the fork 33 to drop of its own weight and engage the pin 34 and releasably hold the latch 27 out of engagement with the rack bar. The spring 31 will then 100 move the latch 28 into engagement with the rack bar and prevent the slide 23 from moving downwardly. A hook 35 is connected with one of the arms 24 of this slide and when the carrying block 15 is moved inwardly, will engage the block and hold it in the adjusted position until the slide has been raised. It will thus be seen that with this construction, the pump locking slide will be 105 releasably held against vertical movement.

under normal conditions and that when the coin is inserted and the plunger moved inwardly, the locking mechanism will be shifted and the slide permitted to be raised but the slide is prevented from moving downwardly upon the rack bar by the latch 28 until the handle of the fork 33 strikes the adjustable abutment 36 mounted upon the rod 37. The fork will then be swung out of engagement with the pin 34 and the latch 27 will be released thus permitting the spring 30 to return the mechanism to the position shown in Fig. 1.

When in use, this coin controlled device is connected with the pump stand and the pump shaft 38 which is in the form of a rack bar will be connected with the slide. It very often happens that a person desiring to purchase gasoline will find the store closed and he is then unable to obtain the necessary supply. With this device, this is overcome, as the purchaser can operate the machine himself without loss to the store-keeper. It is simply necessary to place the necessary coin in the chute 39 and then push the plunger 18 inwardly which will operate the coin controlled mechanism thus releasing the slide and permitting the pump shaft to be operated, by means of a suitable crank. The pump shaft will be raised until the fork 33 strikes the abutment 36 and will then be lowered. It will be impossible to raise the pump shaft a short distance and then lower it and raise it again as the construction prevents this. Therefore the machine can only be operated once thus preventing the purchaser from obtaining more gasoline than is intended for the amount inserted. The amount given for a certain coin can be controlled by adjustment of the abutment 36 and therefore as the price of gasoline varies, the quantity given can be varied accordingly by simply adjusting the abutment.

What is claimed is:—

1. A coin controlled device comprising a housing having an opening in the bottom thereof, a coin carrier slidably mounted in the opening, a rack bar positioned in said housing, and provided with teeth extending in opposite directions, a slide loosely mounted in said housing and provided with arms upon opposite sides of said rack bar, latches pivotally mounted between the arms and adapted to be alternately yieldably held in engagement with the teeth of the rack bar, links pivotally connected with one of said latches and pivotally and slidably engaging the second latch, the first mentioned latch being extended to provide a handle extending into the path of movement of a coin carried by the coin carrier, pins extending beyond the sides of the first mentioned latch, a fork pivotally connected with the arms of said slide and extending to engage said pins when the first mentioned

latch is moved to an inoperative position to releasably hold the latch in an inoperative position, the second latch thereupon being yieldably held in engagement with the teeth of the rack bar, and means for shifting said fork to release the first mentioned latch when the slide has been moved upwardly to a predetermined point. 70

2. A coin controlled device of the character described comprising a housing, a coin holder movably mounted in said housing, a rack bar in said housing provided with oppositely extending teeth, a locking slide loosely mounted in said housing and provided with arms extending upon opposite sides of said rack bar, latches pivotally connected with the arms of said slide and adapted to be alternately yieldably held in engagement with the teeth of said rack bar, links pivotally connected with one of said latches and slidably connected with the second latch, one of the latches being extended into the path of movement of the coin holder for engagement by a coin carried thereby, a drop fork for engaging the first mentioned latch to releasably hold the same in an inoperative position and permit the second latch to move into engagement with the teeth of the rack bar, and means for moving said drop fork to release the latch engaged thereby when the slide has been moved to a predetermined height upon said rack bar. 95

3. A coin controlled device of the character described comprising a housing, a rack bar in said housing, a locking slide in said housing extending upon opposite sides of said rack bar, latches pivotally connected with said slide, links pivotally connected with one latch and slidably connected with the second latch, resilient means yieldably holding the first mentioned latch in engagement with the teeth of the rack bar, resilient means of less strength than the first mentioned resilient means and adapted to yieldably hold the second latch in engagement with the rack bar, means for releasably holding the first mentioned latch out of engagement with the rack bar to permit the second latch to move into engagement therewith, and a coin carrier mounted in operative relation to the first mentioned latch whereby the coin carried thereby may move the first mentioned latch out of an operative position. 100 105 110 115

4. A coin controlled device of the character described comprising a housing, a rack bar in said housing, a locking slide movably mounted in said housing for movement along said rack bar, latches carried by said slide, springs carried by said slide and engaging said latches, links pivotally connected with one latch and slidably connected with the second latch, means carried by said slide for releasably holding the first 120 125 130

mentioned latch in an inoperative position to permit the slide to move upwardly upon the rack bar, a coin carrier mounted in operative relation to the first mentioned latch whereby the coin carried thereby may move the first mentioned latch to an inoperative position, and means for moving the latch holding means to release the first mentioned

latch when the slide is moved to a predetermined point upon the rack bar. 10

In testimony whereof I affix my signature in presence of two witnesses.
